UNITED STATES PATENT OFFICE.

FRED L. EATON, OF REW, PENNSYLVANIA.

PERMUTATION PADLOCK.

1,308,487.

Specification of Letters Patent.

Patented July 1, 1919.

Application filed August 21, 1918. Serial No. 250,824.

To all whom it may concern:

Be it known that I, FRED L. EATON, a citizen of the United States, residing at Rew, in the county of McKean and State of Pennsylvania, have invented certain new and useful Improvements in Permutation-Padlocks, of which the following is a specification, reference being had to the accompanying drawings.

This invention relates to an improved permutation padlock, and has for its primary object to provide a very simply constructed lock of this character whereby the shackle will be securely held in its locked position, and all efforts to open the same by persons unfamiliar with the combination frustrated.

It is another and more particular object of my invention to provide a lock casing, a tube extending therethrough to receive one arm of the shackle, a guide tube extending into the casing for the other arm of the shackle, a series of permutation locking disks engaged through one side of said tube and coacting with the first shackle arm, and an additional locking disk to coact with both arms of the shackle.

It is also a further general object of the invention to provide simple and effective means for supporting the shackle in its open position and effectually preventing the complete withdrawal of the shackle from the lock casing.

And it is a further general object of my invention to provide a permutation padlock which is relatively simple, as well as strong and durable in its construction, highly efficient and reliable in its operation and capable of manufacture at relatively small cost.

With the above and other objects in view, the invention consists in the improved construction, combination and relative arrangement of the several parts as will be herein-after more fully described, subsequently claimed and illustrated in the accompanying drawing in which similar reference characters designate corresponding parts throughout the several views, and wherein:

Figure 1 is a longitudinal sectional view illustrating one embodiment of my improved permutation padlock;

Fig. 2 is an end elevation, partly in section;

Fig. 3 is a horizontal section taken on the line 3—3 of Fig. 1;

Fig. 4 is a section taken on the line 4—4 of Fig. 1;

Fig. 5 is a detail vertical section taken on the line 5—5 of Fig. 1; and

Fig. 6 is a perspective view of one of the permutation locking members.

Referring in detail to the drawings, 5 designates the body wall of the casing, which is of cylindrical form. This casing is closed 65 at one of its ends by the plate 6, and a cap plate 7 is adapted to be fitted upon the other end of said casing. A tube 8 is threaded at one of its ends in the cap plate 7 and at its opposite end in the plate 6. A relatively 70 short tube 9 is threaded in the plate 7 at a diametrically opposite point and projects into the casing. The plate 7 is securely held against removal by means of the screws 10 and 11 respectively. After the screws have 75 been adjusted into engagement with the periphery of the plate 7 the heads of said screws are cut off so as to prevent their removal. A rod 12 is rotatably mounted at one of its ends in the cap plate 7, and upon 80 said rod a locking disk 13 is fixed, said disk being provided with notches or recesses in its periphery at diametrically opposite points, as at 14. A series of telescopically 85 engaged tubes 15 are mounted upon the rod 12 for independent rotation, said tubes projecting longitudinally into the casing and successively increasing in length from the larger to the smaller tube. The largest tube 15 is rotatably mounted in the end wall 6 90 of the case. A locking disk 16 is keyed upon the inner end of each tube 15, said disk being preferably formed with a plurality of keyways 17 so that it may be adjusted upon the tube 15. Each of these disks has a 95 single notch or recess 18 in its periphery. Exteriorly of the lock casing, the tubes 15 project beyond each other and the rod 12 extends beyond the end of the inner tube. To this rod and to the outer end of each 100 tube, a graduated plate 19 is secured. The surface of the end wall 6 of the case is also suitably graduated, and the plates 19 are formed with index projections 20 for movement over the graduated surfaces.

21 designates the shackle having a long arm 22 and a relatively short arm 23. The longer arm is slidably and rotatably en-

gaged within the tube 8 and is formed with a notch 24 coinciding with a slot or opening 25 in the inner side of the tube 8, said notch being adapted to receive the edge of the locking disk 13. The longer arm 22 is also formed with additional spaced notches 26 to coincide with the spaced slots or openings 27 in the tube 8, said latter notches in the shackle receiving the locking disks 16. The shorter arm 23 of the shackle is also provided in its end and at one side thereof with a notch or recess 28 to receive the edge of the locking disk 13.

In the end of the longer arm 22 of the shackle, a pin or stud 29 is fixed and is adapted for movement in a longitudinal slot 30 formed in the wall of the tube 8. This slot at its upper end is angularly or horizontally extended, as at 31.

In the operation of the device, as above described, and assuming that the shackle is securely locked in its closed position, as seen in Fig. 1, when it is desired to open the lock, the plates 19 are turned with respect to each other and in proper predetermined positions as required by the particular combination so as to rotate the several disks 16 relative to each other and dispose the notches 18 thereof in registering relation with the respective notches 26 in the shackle arm. The locking disk 13 is also rotated in a similar manner to position the notches in the edge thereof in coinciding relation with the notches 24 and 28 in the respective shackle arms. The shackle may then be drawn outwardly to dispose the end of its shorter arm 23 beyond the plate 7 of the lock casing, such movement being limited by the engagement of the pin 29 on the long arm of the shackle with the end wall of the slot 30. This shackle arm is then rotated, the pin 29 moving in the angular end 31 of said slot so that the shorter arm of the shackle will be swung laterally. Thus, the shackle may then be readily removed from the staple in which it is engaged. The shackle may be again locked in its closed position by reversing the above operation and forcing the long arm of the shackle inwardly into the tube 8, and turning the several locking disks to engage the same in the notches in the shackle arms. By mounting and arranging the several parts of the lock in the manner described and disposing the disk 13 through the wall of the tube 8 and in engagement with both arms of the shackle, a very strong and durable construction is produced and bending or springing of the central rod 12 will be obviated. The combination may be changed when desired by adjusting the several disks 16 on the ends of the respective tubes 15, as will be readily understood.

From the foregoing description, taken in connection with the accompanying draw-

ings, the construction, manner of operation and several advantages of the device will be clearly and fully understood. The improved lock consists of relatively few parts which are all of simple form so that the device will not be liable to get out of order and can be manufactured at relatively small cost. It will be understood that the lock may be made in various sizes and applied to many different uses for which such a lock would be desirable.

While I have herein shown and described the preferred construction and arrangement of the several parts of my invention, it is nevertheless to be understood that the device is susceptible of considerable modification therein and I, accordingly, reserve the privilege of adopting all such legitimate changes as may be fairly embodied within the spirit and scope of the invention as claimed.

I claim:—

1. In combination, a casing, a tube extending longitudinally therethrough, a shackle having relatively long and short arms and the longer arm being rotatably and longitudinally movable in said tube, said tube being provided with a series of spaced openings and the longer shackle arm having spaced notches to register therewith, said tube being also provided with a slot disposed longitudinally thereof, an outstanding member carried by the longer shackle arm and extending within said slot, a series of permutation locking disks disposed through said openings and engaged in the notches and each having a notch in its periphery to register with the notch in the shackle arm when the disk is rotated to a predetermined position, the longer arm of the shackle having an additional notch therein, the short arm of the shackle being adapted to extend into one end of the casing and also having a notch therein, and an additional rotatable locking disk having notches in its periphery at diametrically opposite points and adapted for engagement in the latter notches in the shackle arms.

2. In combination, a casing, a tube extending longitudinally therethrough, a shackle having relatively long and short arms and the longer arm being rotatably and longitudinally movable in said tube, said tube being provided with a series of spaced openings and the longer shackle arm having spaced notches to register therewith, a series of permutation locking disks disposed through said openings and engaged in the notches and each having a notch in its periphery to register with the notch in the shackle arm when the disk is rotated to a predetermined position, a guide tube projecting into the casing from one end wall thereof and through which the shorter arm of the shackle is adapted to be engaged,

said arm having a notch therein, the longer arm of the shackle being provided with an additional notch, said first named tube having an additional slot in its wall with which the latter notch is adapted to register, and an additional locking disk mounted within the casing for engagement in the latter notches of the shackle arms and provided with notches in its periphery at diametri-

5 cally opposite points to register with the 10 notches in said arms.

In testimony whereof I hereunto affix my signature in the presence of two witnesses.

FRED L. EATON.
